UNITED STATES PATENT OFFICE.

HENRY M. ESSELEN, OF ROSLINDALE, BOSTON, MASSACHUSETTS.

HOUSE-HEATING SYSTEM.

Application filed August 14, 1919. Serial No. 317,451.

To all whom it may concern:

Be it known that I, HENRY M. ESSELEN, a citizen of the United States, and a resident of Roslindale, city of Boston, county 5 of Suffolk, and State of Massachusetts, have invented an Improvement in House-Heating Systems, of which the following description, in connection with the accompanying drawings, is a specification, like 10 characters on the drawings representing like parts.

This invention pertains to improvements in house-heating systems and the like.

In the drawings:—

- 15 Fig. 1 illustrates a preferred form of one embodiment of my invention as applied and practiced in connection with a diagrammatic house-heating system of the so-called "vacuum" type;
- 20 Fig. 2 illustrates a preferred form of one embodiment of my invention as applied and practiced in connection with a diagrammatic house-heating system of the so-called "steam pressure" type; and
- 25 Figs. 3 and 4 show preferred forms of control devices for starting and stopping preferred forms of pump for circulating air through the system.

In Fig. 1 is shown a steam boiler 3 having a steam dome 4, a steam outlet line 5 connected to a radiator 6, which is preferably supplied, as shown, with a return line 7 connected near the bottom of the boiler.

In systems of this type, each radiator is 30 commonly supplied with an air valve 8, which is ordinarily piped to some form of exhaust apparatus usually of the siphon type. This siphon is used to exhaust the air from the system so that the vapor from the heated water in the boiler will circulate through the system without necessitating any pressure in the system above atmospheric pressure.

I have found that the efficiency of 35 systems of this type is greatly increased by providing air inlet means preferably connected, as shown, to supply air to the boiler at a point below the water level thereof and preferably at the bottom thereof. In 40 the preferred form of my invention shown in the drawings, the pipe 9 is open to the atmosphere at 10 and passes through the smoke chamber 11 so that the air in the pipe 9 is somewhat heated, the pipe 9 being in 45 the preferred form of my invention illustrated connected at 12 to the return line 7

at a point between the boiler and the usual check valve 13. Of course the connection of the pipe 9 to the return line is merely convenient, and it may be connected to the boiler directly or in any other suitable way. The valve 8 is connected by a pipe 14 to any suitable exhaust apparatus indicated at 15, which preferably takes the form of a suction pump operated by an electric motor which is adapted to be stopped and started in any suitable way, but preferably automatically, and directly or indirectly by a thermostatic control, through a snap switch.

In Figs. 3 and 4, I have shown preferred forms of control devices for starting and stopping preferred forms of pump for circulating air through the system. In the preferred form of apparatus shown in Fig. 3, primarily adapted for use in that form of my invention illustrated in Fig. 1, I have shown a thermostatic element 100, preferably, as illustrated, enclosed in a shell 101 into which vapor may be introduced from the system or which may be merely subjected to the changes in temperature in a portion of the space to be heated by the system. As the temperature rises, the thermostatic device 100 contracts until the end thereof contacts with the electrical contact 102, thus 50 closing the circuit from the battery 103 and energizing the coil about the solenoid 104, thereby rocking the switch fulcrumed at 105 and withdrawing the knife switch 106 so that the circuit between the wires 107 and 55 108, previously supplying current to the pump-actuating motor 110, may be broken. Conversely, as the temperature lowers, the thermostatic device 100 will straighten until the end thereof touches the electrical 60 contact 111, thereby closing the circuit including the battery 103 to energize the coil about the solenoid 112, thereby rocking the knife switch 106 back into the position illustrated in the drawings so as to again 65 close the circuit between the wires 107 and 108, thereby energizing the motor 110. The motor 110 in the preferred form of my invention illustrated in Fig. 3, reciprocates the piston 113 of a suction pump having a 70 cylinder 114, thereby sucking air in through the inlet valve 115 from the pipe 14 and expelling said air through the exhaust valve 116 into the exhaust pipe 117.

That form of my invention shown in Fig. 4 is substantially identical with that illustrated in Fig. 3, except that the pump in-

- cluding the cylinder 114 and piston 113, is of the type primarily adapted for use in connection with that form of my invention illustrated in Fig. 2 of the drawings, so that 5 the air supplied to the boiler is under pressure greater than the atmosphere, instead of being actuated by suction as in the device shown in Figs. 1 and 3 of the drawings. To this end, air may be drawn in through 10 the inlet pipe 130 and inlet valve 131, being discharged under pressure through the discharge valve 132, thence into the pipe 9' (see also Fig. 2) under a pressure sufficiently great to overcome the head of the water in 15 the boiler and, where the pressure in the system is greater than the atmospheric pressure, providing a sufficient pressure to overcome whatever pressure there may be in the system as a whole.
- 20 Air entering the pipe 9' at 10 passes through the smoke chamber 11 and is somewhat heated, thence passes into the bottom of the boiler through the return line 7, passes up through the water in the form 25 of bubbles, taking up water vapor as it passes through the water and improving the circulation, and thence passes into the steam or vapor dome 4 and thence through the pipe 5' into the radiator 6. The air not 30 only carries considerable heat, but is a superior carrier for the water vapor and improves the circulation in the system.

In Fig. 2, which shows diagrammatically my system and method as applied to a 35 house-heating boiler of the steam pressure type, 3' is the boiler, 4' the steam dome, 5' the steam outlet line, 6' the radiator and 7' the return line, and 8' is an air valve of the usual thermally controlled type. I have 40 shown the pipe 9' passing from any suitable compressor 15', hereinafter more fully described, through the smoke chamber 11' and thence entering the boiler at 12'. The pipe 9' may, if desired, be connected to the 45 boiler through the return line 7' at a point between the boiler and the check valve 13'. The compressor 15' is preferably electrically operated, the supply of energizing current to the motor being automatically controlled 50 by a thermally operated snap switch.

When the temperature in the house falls below a given point, the compressor 15' is started pumping the air through the pipe 9' into the boiler, where it passes in the 55 form of bubbles up through the water and thence into the steam dome, passing through the pipe 5' into the radiator 6', where it is separated from the steam by the air valve 8'. As in the vacuum system before described, the air serves not only as a heating medium, but also as a superior carrier for the water vapor and steam, and also assists the circulation of the steam through the system.

While I have shown and described two 65 embodiments of my invention as applied to steam and vacuum systems, it will be understood that changes involving omission, substitution, alteration and reversal of parts, and even changes in the mode of operation, 70 may be made without departing from the scope of my invention, which is best defined in the following claims.

Claims:

1. In a house-heating system including 75 a boiler, and a radiator having supply and return lines connected thereto, an air inlet conduit connected to the boiler below the water level therein to produce heated moisture laden air bubbles in the boiler 80 whereby to assist circulation therein and to produce aerated vapor for circulation in the radiator, an air outlet conduit connected to the radiator at the end opposite the vapor supply line connection and an air 85 pump connected to one of said conduits.

2. In a house-heating system including 90 a boiler, and a radiator having supply and return lines connected thereto, an air inlet conduit connected to the boiler below the water level therein to produce heated moisture laden air bubbles in the boiler 95 whereby to assist circulation therein and to produce aerated vapor for circulation in the radiator, an air outlet conduit connected to the radiator at the end opposite the vapor supply line connection and a thermally controlled air pump connected to one of said conduits.

3. In a house-heating system including 100 a boiler, and a radiator having supply and return lines connected thereto, an air inlet conduit connected to the boiler below the water level therein to produce heated moisture laden air bubbles in the boiler 105 whereby to assist circulation therein and to produce aerated vapor for circulation in the radiator, an air injector connected to said inlet conduit and an air vent connected to the radiator above the return line connection thereto.

4. In a house-heating system including 115 a boiler, and a radiator having supply and return lines connected thereto, an air inlet conduit connected to the boiler below the water level therein to produce heated moisture laden air bubbles in the boiler 120 whereby to assist circulation therein and to produce aerated vapor for circulation in the radiator, a thermally controlled air injector connected to said inlet conduit, an air vent connected to the radiator above the return line connection thereto and an automatic valve in said air vent.

In testimony whereof, I have signed my 125 name to this specification:

HENRY M. ESSELEN.
